UNITED STATES PATENT OFFICE.

HOWELL JORDAN, OF LOS ANGELES, CALIFORNIA.

DESIGN FOR A COMBINED CAR-HANDLE AND SHIELD.

50,446.

Specification for Design.

Patented Mar. 13, 1917.

Application filed February 10, 1915. Serial No. 7,368. Term of patent 14 years.

To all whom it may concern:

Be it known that I, HOWELL JORDAN, a citizen of the United States, residing at Los Angeles, in the county of Los Angeles and State of California, have invented a new, original, and ornamental Design for a Combined Car-Handle and Shield, of which the following is a specification, reference being had to the accompanying drawing, forming a part thereof.

Figures 1 and 2 are perspective views of the device illustrating my design.

Fig. 3 is a plan view.

I claim:

The ornamental design for a combined car handle and shield, as shown.

HOWELL JORDAN.
